CLAIM

We claim the ornamental design for a luminaire, as shown and described.

DESCRIPTION

FIG. 1 is a perspective view of a luminaire according to a first configuration.

FIG. 2 is a first side view of the luminaire shown in FIG. 1.

FIG. 3 is a second side view of the luminaire shown in FIG. 1.

FIG. 4 is a third side view of the luminaire shown in FIG. 1.

FIG. 5 is a fourth side view of the luminaire shown in FIG. 1.

FIG. 6 is a top view of the luminaire shown in FIG. 1.

FIG. 7 is a bottom view the luminaire shown in FIG. 1.

FIG. 8 is another perspective view of the luminaire shown in FIG. 1.

FIG. 9 is another perspective view of the luminaire shown in FIG. 1.

FIG. 10 is a perspective view of a luminaire according to a second configuration.

FIG. 11 is a first side view of the luminaire shown in FIG. 10.

FIG. 12 is a second side view of the luminaire shown in FIG. 10.

FIG. 13 is a third side view of the luminaire shown in FIG. 10.

FIG. 14 is a fourth side view of the luminaire shown in FIG. 10.

FIG. 15 is a top view of the luminaire shown in FIG. 10.

FIG. 16 is a bottom view the luminaire shown in FIG. 10.

FIG. 17 is another perspective view of the luminaire shown in FIG. 10; and,

FIG. 18 is another perspective view of the luminaire shown in FIG. 10.

Any broken lines represent unclaimed subject matter and form no part of the claimed design. Any dash-dot broken lines represent boundary lines. The dash-dot broken lines themselves form no part of the claimed design.
